FINGERPRINTING APPARATUS

Herman J. Doepner, St. Paul, Minn.

Application April 5, 1943, Serial No. 481,877

5 Claims. (Cl. 41—4)

My invention relates to an improvement in fingerprinting method and apparatus, wherein it is desired to provide a method for and an apparatus capable of taking a clear fingerprint.

In the past two general methods have been employed in taking fingerprints. The first of these methods includes the inking of the fingers in any conventional manner and placing them individually down upon a suitable card or paper provided for the purpose of receiving the prints. The resulting impression is commonly referred to as a "plain" fingerprint. The second method commonly employed comprises placing the inked fingers individually upon a card or sheet prepared for the purpose, and rolling each individual finger about its longitudinal axis to obtain a print not only of the finger pad or under side of the finger, but also of a portion of the sides thereof. Such an impression is commonly referred to as a "rolled" fingerprint.

Advantages may be found for both methods of taking fingerprints as above described. The first of these methods is sometimes desired, as perhaps a more correct, true impression results. However, the impression of but a small and inadequate area of the fingers is thus obtained. The second of the above described methods is sometimes preferred because of the greater or adequate area of the finger which is included in the impression. Unless such prints are taken with extreme care, however, blurring and blotching of the prints is likely to result, and often the correct distances between the papillary ridges or the width of the intervening furrows is not exact.

The object of the present invention is to avoid the difficulties now experienced with existing methods of taking fingerprints and to provide a method of, and apparatus for, obtaining impressions which will at all times show the papillary ridges and intervening furrows in their proper relation, and thereby facilitate and assure correct interpretation.

A feature of the present invention resides in the fact that true and undistorted reproductions of the natural fingerprint patterns are received through the use of my method and my apparatus. As a result more correct and efficient classification and filing may be obtained, thereby simplifying the task of searching and more certainly finding a duplicate print in the fingerprint records.

A further object of the present invention lies in the fact that correct collation of two prints suspected or regarded of being alike is assured.

Thus the identity of an individual may be correctly and more easily established than has been possible in the past. This is of extreme importance, particularly where fingerprints are used as a means identification, especially where they may be employed as evidence in civil or criminal court cases.

A feature of the present invention lies in the provision of a base for a fingerprinting sheet or card, and in providing a flexible support beneath a portion of this sheet or card which will permit the card to follow the contour of the finger while the fingerprint is being taken. As a result there is no danger of blurring or blotching the impression due to improper rotation of the finger relative to the paper. Furthermore the resilient or flexible means supporting the paper or card upon which the impression is being taken is such as to insure accurate contact between the finger and the card at all times.

A feature of the present invention lies in the provision of a support for a card or sheet upon which a fingerprint or impression is to be made, and to provide this support with yielding portions into which the card or paper sheet may be pressed. These yielding portions are so devised as to hold the card or sheet against the finger as the finger depresses the paper, thereby producing a print of both the under surface of the finger and the beveled or rounded sides thereof without requiring a rotary movement of the finger. As a result of the elimination of the ever-present awkwardness in connection with the rotary movement, a true pattern of the finger is impressed upon the paper and no blurring of the print is likely to result. Moreover, the alternate light and dark shading as well as occasional solid blotches of ink commonly present in rolled impressions are eliminated, and a print of uniform color and legibility is obtained.

In carrying out my invention I prefer to use a card or paper sheet supporting device including depressible portions into which the sheet or card may flex and to slide a resilient or flexible supporting element beneath the sheet so as to hold the sheet into contact with the lower surface and rounded edges of the finger.

These and other objects and novel features of my invention will be more clearly and fully set forth in the following specification and claims.

In the drawing forming a part of my specification:

Figure 1 is a front perspective view of my fingerprint apparatus, showing the construction thereof.

Figure 2 is a sectional view through the apparatus for taking fingerprints, the position of the section being indicated by the line 2-2 of Figure 1.

Figure 3 is a transverse sectional view through a modified form of apparatus.

Figure 4 is a sectional view through one end of the modified form of construction shown in Figure 3, the position of the section being indicated by the line 4-4 of Figure 3.

The fingerprint apparatus A, illustrated in Figures 1 and 2 of the drawing, comprises substantially rectangular sub-base 10 having mounted thereupon a multislot base 11. The base 11 in the particular form of construction illustrated, is of generally rectangular form and includes a pair of spaced slots 12 and 13, which are separated by an intermediate partition member 14 formed in the base 11 between the slots 12 and 13. It will be noted that the slot 12 is wider than the slot 13 for a purpose which will be more clearly pointed out later in the specification. A larger number of slots of varying widths, similar to the slots 12 and 13, could be formed if it were thought desirable or necessary. I have found, however, that the two slots shown are ample for most purposes. If desired the construction may be modified by substituting a movable center piece 14, such as a roller, instead of the rigid style shown in the drawing.

Overlying the upper surface of the base 11 and extending substantially the full depth of the slots 12 and 13, I provide an impresser 15. The impresser 15 comprises one or more plies of rubber or other elastic or resilient material secured across the tops of the slots 12 and 13 in a manner to cover the same. While a single ply of rubber or other resilient material is capable of accomplishing good results, I have found that better prints will result with less difficulty if two or more plies of rubber are used to form the impresser. In my experience I have found that the prints have less tendency to blur when more than a single ply of material is used.

Overlying the impresser 15 I provide a bi-winged table 16, which is slotted at 17 and 19. These slots 17 and 19 register with the slots 12 and 13 respectively, so that the impresser 15 is exposed throughout the area of the upper extremity of the slots 12 and 13. The table 16 is held in place by screws 20 or other suitable means which extend through the table 16, the impresser 15, and into the base 11.

A series of spring clips 21 are secured to the table 16 adjacent the forward edge thereof. These clips 21 are aligned and form a guide to hold a card or strip of paper square with respect to the table 16. Thus a card or strip of paper may be placed upon the table 16 to overlie one or both of the slots 12 and 13 in position to receive a fingerprint. The use of such clips is optional as they are not absolutely necessary.

In taking a print a strip of paper, either in desired length, or from a roll or a suitable card of paper or similar material is laid over the desired slot 12 or 13 and held in position by the prongs 21. The finger to be impressed is inked in any conventional manner and is placed vertically over the card in registry with the slot 12 or 13. The finger is firmly depressed into the slot until the back of the finger is more or less substantially level with the table 16. A uniform impression is left upon the card or strip by pressure of the impresser 15 against the under-

surface of the same. This downward pressure against the elastic impresser yields an impression of the fingerprint pattern on the ball of the finger, as well as of the rounded or bevelled sides (including a part of the tip) thereof, in such a manner as to retain the natural intervals between the ridges. I have found that this method retains the fine distinctiveness of the characteristics of the fingerprint pattern and avoids the inequalities and blurring which usually accompany the rotary process of making rolled impressions. The print is true and undistorted and substantially the whole printable area of the fingerprint pattern is impressed upon the paper, thereby making filing and identification much more complete than would otherwise be possible.

I have found that this process of taking fingerprints results in greater legibility of the prints, the printing of a larger area of the fingerprint pattern, as well as a more faithful reproduction of the natural pattern. As a result my prints lead to greater accuracy in classification, filing and finding. I therefore believe that greater efficiency in classification, filing and finding may be obtained. I have found that my process is of particular advantage in a monodactilar classification system, although by properly positioning the prints or by taking them individually on the bottom margin of the standard 8" x 8" card, my process will operate with greater efficiency in a decodactilar classification system. When desired, the notches 12 and 13 may extend entirely through the base 11 to accommodate an impression card of any size.

It will be noted that the base 11 is provided with slots 12 and 13 of varying widths. My method may be accomplished through the use of a single slot, such as the slot 12 which is sufficiently wide to accommodate any of the fingers or the thumbs. I have found, however, that by using a slot which is not greatly wider than the finger of which the print is being taken, better prints will result and it is not necessary to depress the impresser 15 to so great an extent as would otherwise be necessary. In other words, in order to obtain a print of the base and rounded sides of a narrow finger, it would be necessary to depress the impresser 15 deeply into the slot if the slot were much wider than the finger. On the other hand, if the slot is relatively narrow the same area may be impressed upon depressing the finger to the extent shown in Figure 2 of the drawing where the slot is narrower.

In Figures 3 and 4 of the drawing I disclose a modified form of construction B which is capable of accomplishing similar results to that shown in Figures 1 and 2 without the use of a rubber or elastic impresser plate. This construction B includes a sub-base 22 having a multi-slotted base 23 mounted thereupon. A bi-winged table 24, similar to the table 16, is secured to the top of the base 23 so that in outward appearance the apparatus B is very similar to the apparatus A.

The base 23 includes a relatively wide slot 25 having a somewhat narrower slot 26, similar to the notches 12 and 13 in the base 11. The opposite ends 27 and 29 of the base 23 are hollowed out to enclose resilient members which will be later described. A transversely extending pivotally mounted roller 30 is provided in each end of the base 23. The rollers 30 are spaced slightly below the undersurface of the table 24 so as to form a

slot 31 between each roller 30 and the table 24 to accommodate a flexible belt or support 32.

The flexible belt or tape 32 passes through the slots 31 and through a slot 33 between a roller 28 mounted above and forming a part of the central partition 34 and the lower surface of the table 24. Thus the belt or tape 32 is free to move longitudinally. Springs 35 are secured to each end of the belt or tape 32 resiliently connecting the belt ends to anchoring elements 36 which are secured at the lower extremity of the ends 27 and 29 of the base 23. A reinforcing clip 38 may be provided at each end of the belt 32 to strengthen the same. Thus when the belt 32 is depressed by pressure of a finger resting upon the same the springs 35 may stretch, permitting the belt or tape 32 to flex into the slots 25 or 26 in much the same manner as though the belt 32 were formed of elastic or resilient material.

In taking an impression with the apparatus illustrated in Figures 3 and 4 of the drawing, a strip or card is laid upon the surface of the table 24 and held in place by clips 37, similar to the clips 21 on the table 16. The finger is inked in any suitable or convenient manner and is placed upon the paper card or strip, directly above either the slot 25 or the slot 26. Downward pressure of the finger against the card acts to flex the belt or tape 32 into the slot 25 or 26, the springs 35 drawing the card closely about the bottom of the finger and the rounded sides thereof. The purpose of forming the base 23 with two or more slots such as 25 and 26 of varying width has been explained in connection with the apparatus A. I have found that excellent prints may be taken of the terminal and parts of the middle phalanges of the fingers and the crease between them in which the ridges of the fingerprint pattern are all illustrated in their true relationship. Thus my prints have the advantage of the rolled impression in area, with the accuracy of a plain impression. In other words, in taking the fingerprint impression the finger is moved vertically as in the case of a plain impression, but at the same time a greater area of the finger is imprinted as in the case of a rolled fingerprint.

In accordance with the patent statutes, I have described the principles of construction and operation of my fingerprint method and apparatus, and while I have endeavored to set forth the best embodiments thereof, I desire to have it understood that obvious changes may be made within the scope of the following claims without departing from the spirit of my invention.

I claim:

1. Fingerprint apparatus comprising a base

having a recess therein, a top having a corresponding recess, a sheet of rubber-like material between the base and the top, and means to hold the impression sheet in overlying relation over said rubber-like sheet, whereby when the finger is pressed downwardly upon said impression sheet the rubber-like sheet deforms to the shape of the finger, thereby producing an impression of the end as well as the front of the finger.

10 2. Fingerprint apparatus comprising a base having a recess therein, a sheet of rubber-like material overlying the base and the recess, and means engaging marginal edges of the sheet to hold the sheet properly anchored relative to the base, said rubber-like sheet being adapted to support an impression sheet overlying the same, whereby when the finger is pressed downwardly upon said impression sheet, the rubber-like sheet deforms to the shape of the finger thereby producing an impression of the end as well as the front of the finger.

15 3. Fingerprint apparatus comprising a base having a recess therein, a sheet of rubber-like material overlying the recess and extending marginally over said base along the sides of the recess, means securing the rubber-like sheet in position upon the base, said rubber-like sheet being adapted to support an impression sheet in overlying relation to said rubber-like sheet, whereby when the finger is pressed downwardly upon the impression sheet, the rubber-like sheet deforms to the shape of the finger, thereby producing an impression of the end as well as the front of the finger.

20 30 4. Fingerprint apparatus comprising a base having a recess therein, a rubber-like sheet overlying said recess and being anchored marginally to said base, and an impression sheet adapted to overlie said rubber-like sheet, whereby when the finger is pressed downwardly upon said impression sheet, the rubber-like sheet deforms to the shape of the finger, thereby producing an impression of the end as well as the front of the finger.

45 5. A fingerprint apparatus comprising a base having a pair of recesses therein, a top having corresponding recesses, a sheet of rubber-like material between the base and the top, and means to hold an impression sheet in overlying relation over said rubber-like sheet, whereby when the finger is pressed downwardly upon said impression sheet, the rubber-like sheet deforms to the shape of the finger, thereby producing an impression of the end as well as the front of the finger.
